UNITED STATES PATENT OFFICE.

ANTHONY B. ZIERLEYN, OF GRAND RAPIDS, MICHIGAN.

ELECTRIC TIME-SWITCH.

No. 824,054.

Specification of Letters Patent.

Patented June 19, 1906.

Application filed December 1, 1905. Serial No. 289,841.

To all whom it may concern:

Be it known that I, ANTHONY B. ZIERLEYN, a citizen of the United States, residing at Grand Rapids, in the county of Kent and State of Michigan, have invented a new and useful Electric Time-Switch, of which the following is a specification.

This invention relates to electric time-switches, and has for its principal object to provide a means for automatically connecting and disconnecting an electric circuit so that the circuit may be closed or broken for any desired length of time.

A further object of the invention is to provide a timing device of this character in which the time of closing the circuit and the time of opening the circuit may be adjusted independently of each other.

A still further object of the invention is to provide an electric time-switch of simple and inexpensive construction and which may be connected at comparatively small cost to an ordinary clock-train.

With these and other objects in view, as will more fully hereinafter appear, the invention consists in certain novel features of construction and arrangement of parts hereinafter fully described, illustrated in the accompanying drawings, and particularly pointed out in the appended claims, it being understood that various changes in the form, proportions, size, and minor details of the structure may be made without departing from the spirit or sacrificing any of the advantages of the invention.

In the accompanying drawings, Figure 1 is a rear elevation, partly in section, of an electric time-switch constructed in accordance with the invention. Fig. 2 is a transverse sectional view of the same on the line 2-2 of Fig. 1. Fig. 3 is a sectional plan view of the device on the line 3-3 of Fig. 1. Fig. 4 is a transverse sectional view of a portion of the device on the line 4-4 of Fig. 1. Fig. 5 is a face view of the clock-dial. Fig. 6 is a detail perspective view of one of the circuit-closing members detached.

Similar characters of reference are employed to indicate corresponding parts throughout the several figures of the drawings.

The apparatus is mounted in a suitable support including a base 10 and standards or brackets 11, both of which are formed of porcelain or other insulating material. The upper ends of the brackets or standards are

preferably curved to form a seat for the casing 12 of a clock.

The clock-train includes a cannon-pinion 13, which intermeshes with two gears 14 and 15 of equal size, said gears being loosely mounted on arbors 16 and 17, respectively, and these arbors are provided at a point in front of the clock-dial with knobs 19, by which they may be turned for the purpose of adjusting the time of operation of the switch mechanism. Each arbor carries a small pointer 20, that is movable over a dial, there being two dials 21 and 22, one to indicate the time set for closing the circuit and the other to indicate the time set for opening the circuit, and these are adjustable independently of each other in much the same manner as an ordinary alarm mechanism is set.

The gears 14 and 15 are each provided with integral hubs 24, carrying timing-cams 25 of the type ordinarily employed in alarm-trains, and these are arranged to engage lugs 26, projecting from collars 27, that are rigidly secured to the arbors 16 and 17, the collars being turned until the lugs are adjusted any desired distance from the shoulders of the cams, and said cams being arranged to make one complete rotation each twelve hours. Bearing against the hubs 24 are the upper bifurcated ends of levers 30 and 31, pivoted in suitable brackets 32, and the lower ends of which serve to control the movement of the circuit-closing device. The upper ends of these arms are forced into engagement with the hubs 24 by means of springs 33, and as soon as one of the shoulders of one of the timing-cams comes opposite one of the lugs 26 the timing-cam and hub will move outward under the influence of spring 33, and the circuit-controlling lever will be swung on its pivot for the purpose of releasing one of the circuit-controlling members.

At a central point under the clock-train is arranged a metallic standard 36, carrying a pair of slightly-spaced metallic plates 37, arranged for the reception of the opposite ends of a pair of switch-blades 39 and 40, and when both blades are engaged with the plate 37 the lighting or other circuit is closed, and when either is disconnected the circuit is open.

The switch-blade 39 is carried by a block 41, formed of porcelain or other material, and the rear end of the blade is connected mechanically and electrically to a stem 42, that is arranged to slide within a recess formed be-

tween a pair of metallic plates 43 and 44, that are secured between the base 10 and bracket 11, the lower plate 44 being extended at one side and carrying a binding-screw 45 for connection to one of the wires x of the circuit. The stem has a reduced portion 46, carrying a fixed flange or collar 47 and provided at its outer end with a knob 48, formed of insulating material, for the purpose of manually adjusting the position of the switch-blade. The reduced portion of the stem is surrounded by a helical compression-spring 50, bearing at one end against the collar 47 and at the opposite end against a lug 51, carried by the lower plate 44 and provided with an opening for the passage of the reduced portion of the stem. This spring tends normally to move the stem outward from the position shown in Fig. 1, and thus pull the switch-blade 39 from engagement with the plates 37. The switch-blade 39 is held from rotative movement by a pair of flanges 53, (see Fig. 2,) formed integral with the base 10 and engaging the ends of the blades which project beyond the block 41. The block 41 is provided with a vertically-disposed opening 54, in which is arranged a helical compression-spring 55, held in place by upper and lower plates 56, secured to the block. These plates are provided with openings for the passage of a vertically-movable rod 58, carrying at its upper end a catch 59, beveled on one face and provided with an abrupt vertical shoulder designed to engage with the clock-controlled lever 31, and when so engaged the lever will hold the switch-blade 39 in engagement with the plates 37; but when lever 31 is moved at the end of a predetermined period of time to one side of the catch 59 the spring 50 will withdraw the blade 39 from engagement with the plates 37 for the purpose of breaking the circuit. The blade 40 is also mounted in a block 41, which carries a spring-pressed catch 59', of a construction similar to the catch 59, and the stem 42', attached to the blade 40, is acted upon by a spring 50', which tends to move the blade 40 into engagement with the catch 59'. The upper end of the stem is provided with a knob 48' to permit manual adjustment of the position of the blade 40. The catch 59' is engaged by the lever 30 and held by said lever with the blade 40 in the position shown in Fig. 1—that is to say, out of contact with the plates 37. The stem 42' is guided between two plates 43' and 44', the lower plate 44' carrying a binding-screw 45' for connection to a circuit-wire x' .

The normal position of the parts is shown in Figs. 1 and 3, with the blade 40 out of engagement with the plates 37 and the blade 39 engaging said plates 37, the circuit being broken. The pointers 20, carried by the arbors 16 and 17, are then adjusted to time the closing of the circuit and the subsequent

opening of the circuit, and at the proper time lever 30 will be released and forced to move by its spring from engagement with the catch 59', whereupon the spring 50' will act to force the blade 40 into engagement with the plates 37, thus completing a circuit from line x' through binding-screw 45', plates 44' 43', stem 42', blade 40, plates 37, blade 39, stem 42, plates 43 44, binding-screw 45, and circuit-wire x . The circuit will then be closed until the gear 15 in rotating carries its cam to a position to release the lever 31, whereupon said lever is forced by its spring from engagement with the catch 59 and spring 50 immediately withdraws the blade 39 from engagement with the plates 37, breaking the circuit. It will be seen that the time of closing the circuit and the time of opening the circuit may be independently adjusted and the current may be kept on for any desired length of time, this being of especial value in many cases where it is desired to avoid waste of current—as, for instance, in the lighting of a show-window during a portion of the evening or the lighting of a store after the closing hour, so that a light may be kept burning throughout the night and extinguished early in the morning.

Having thus described the invention, what is claimed is—

1. In an electric time-switch, the combination with a time-train, of a pair of independently-adjustable timing devices receiving motion, therefrom, independently-operable circuit-controlling members, one of which is movable to close the circuit, and the other to break the same, springs tending to operate said members, levers under the control of the timing devices, said levers normally holding the circuit-closing members from movement, and a central contact member with which both of said circuit-closing members engage to close the circuit.

2. In an electric time-switch, the combination with a base, of a pair of spaced metallic plates, switch-blades forming circuit terminals and arranged by engagement with said plates to close the circuit, blocks carrying said blades, metallic stems secured to the blades and provided with knobs or handles for manual adjustment, springs acting on said stems and tending to move the blocks, spring-actuated catches carried by said blocks, a pair of pivotally-mounted levers engaging with the catches, and independently-adjustable timing devices controlling the movement of said levers.

3. In an electric time-switch, the combination with a base and brackets, of a clock mechanism supported by the brackets; a pair of metallic plates arranged between the brackets, circuit-closing blades arranged to engage between the plates, the base having webs or flanges for guiding said blades, metallic stems carrying the blades, metallic plates ar-

ranged between the base and bracket members, and arranged to form sockets for the stems, springs acting on said stems and tending to move the blades, spring-actuated catches carried by the block, a pair of levers pivoted to the clock-train and arranged to engage the catches, springs tending to actuate said levers, timing-cams for controlling the movement of the levers, and an adjust-

able arbor having a collar for timing the operation of each cam.

In testimony that I claim the foregoing as my own I have hereto affixed my signature in the presence of two witnesses.

ANTHONY B. ZIERLEYN.
